STRUCTURAL STEEL MEMBER

Timothy Collins, San Francisco, Calif., assignor
of one-half to Benjamin F. Tomlin, San
Francisco, Calif.

Application January 7, 1938, Serial No. 183,848

3 Claims. (Cl. 189—37)

This invention relates to a method of making structural steel members and the product obtained.

The object of the present invention is to generally improve and simplify the construction of structural steel members such as wall and partition studs, ceiling joists, roof rafters, and the like, to provide a method whereby such members may be economically made from flat metal strips 10 without waste of material, and further to provide a method whereby an expanded structural member is formed by cutting, folding and bending operations only.

The method employed and the product obtained is shown by way of illustration in the accompanying drawings, in which

Fig. 1 is a plan view of an elongated metal strip from which the product shown in Fig. 3 is obtained, said figure showing the manner in 20 which the strip is cut longitudinally and transversely;

Fig. 2 is a perspective view of the metal strip showing the connecting arms bent at right angles to the flat surface of the strip, and said arms being partially expanded;

Fig. 3 is a perspective view showing the final product;

Fig. 4 is a perspective view of a portion of the final product showing a reinforcing bar secured between the central arm connectors;

Fig. 5 shows a portion of the metal strip and the cut-out portion whereby a bending lug is formed on the central connector between the arms;

Fig. 6 is a perspective view showing the bending lug before and after bending;

Fig. 7 is a view similar to Fig. 1, showing a slightly different manner of cutting the metal strip prior to forming and bending;

Fig. 8 shows the first forming operation;

Fig. 9 shows the cross-arms partially expanded;

Fig. 10 shows the final product, said product being identical to the product shown in Fig. 3 but varying therefrom to the extent that the connecting cross-arms are angle-shaped in cross-section and that the central U-shaped connectors are widened to receive a central reinforcing channel bar;

Fig. 11 is a view similar to Figs. 1 and 7, showing another manner of cutting the metal strip prior to forming and bending;

Fig. 12 is a perspective view showing the first forming and bending operation;

Fig. 13 shows the final product with the cross-arms completely extended;

Fig. 14 is a view similar to Figs. 1, 7 and 11, showing still another method of cutting the 60 metal strip prior to forming and bending;

Fig. 15 is a perspective view showing the first forming and bending operation;

Fig. 16 shows the cross-arms partially expanded or extended; and

Fig. 17 is a perspective view showing the final 5 product with the cross-arms fully extended.

Referring to the drawings in detail, and particularly Figs. 1 to 3, inclusive, in which a structural steel member is shown, this member is formed from a flat elongated metal strip generally indicated at A (see Fig. 1). This strip is first cut at suitable spaced intervals along lines 10 2, 3 and 4, parallel to the sides of the strip, and then transversely as at 5, to form a pair of side strips 6—6 and pairs of connecting arms 7—7.

The arms are connected to the side strips by portions 8—8 and to each other by members 9. The arms and the connecting portions 8—8 are bent at right angles to the flat surface of the side strips to stand on edge with relation there-

to as shown in Fig. 2, the connecting portions 9 of each pair of arms being bent centrally upon themselves at the same time to form U-shaped central connectors, the inner faces of which may contact each other or be separated, as will hereinafter appear. The arms are next bent at right angles to the portions 8—8, as shown at 10—10,

and also at right angles to the central connectors 9, as shown at 11—11, and will thus spread the side strips apart and form connecting cross-arms between the side strips, as clearly shown 20 in Fig. 3. Thereafter, the side strips are bent to 25

form side flanges 12—12 and webs 13—14.

Fig. 4 is a perspective view of a portion of the final product showing a reinforcing bar secured between the central arm connectors;

Fig. 5 shows a portion of the metal strip and the cut-out portion whereby a bending lug is formed on the central connector between the arms;

Fig. 6 is a perspective view showing the bending lug before and after bending;

Fig. 7 is a view similar to Fig. 1, showing a slightly different manner of cutting the metal strip prior to forming and bending;

Fig. 8 shows the first forming operation;

Fig. 9 shows the cross-arms partially expanded;

Fig. 10 shows the final product, said product being identical to the product shown in Fig. 3 but varying therefrom to the extent that the connecting cross-arms are angle-shaped in cross-section and that the central U-shaped connectors are widened to receive a central reinforcing channel bar;

Fig. 11 is a view similar to Figs. 1 and 7, showing another manner of cutting the metal strip prior to forming and bending;

Fig. 12 is a perspective view showing the first forming and bending operation;

Fig. 13 shows the final product with the cross-arms completely extended;

Fig. 14 is a view similar to Figs. 1, 7 and 11, showing still another method of cutting the 60 metal strip prior to forming and bending;

Fig. 15 is a perspective view showing the first forming and bending operation;

Fig. 16 shows the cross-arms partially expanded or extended; and

Fig. 17 is a perspective view showing the final 5 product with the cross-arms fully extended.

cutting out a portion of the metal strip of each connector, as indicated at 18 in Fig. 5.

In Figs. 7 to 10, inclusive, a slightly modified form of the structure shown in Figs. 1 to 6 is disclosed. The metal strip (see Fig. 7) is cut in a manner identical to the strip shown in Fig. 1, but in addition thereto two short transverse cuts are made in connection with each set of cross-arms, as indicated at 19 and 20. The strip is first folded and bent as shown in Fig. 8. It is then expanded until the cross-arms assume the position shown in Fig. 10, the partially expanded position of the cross-arms being shown in Fig. 9. The only manner in which this product differs from the product shown in Fig. 3 is that the legs of the U-shaped central connectors are spaced apart so as to permit the insertion of a reinforcing channel bar or similar member as indicated at 21 (see Fig. 10), and that the cross-arms are bent to form angle bars as shown at 22. Bending the cross-arms to make their cross-section conform to an angle bar obviously stiffens and reinforces the structural member as a whole, and it is further stiffened and reinforced by insertion of the channel bar 21 or a similar member. It will also be obvious that the load-bearing factor of the structural member is thereby increased, permitting the structural member to be used for numerous purposes.

In Figs. 11 to 13, a further modification is disclosed. The sheet is cut along the lines indicated at 24, 25 and 26, parallel to the outer edges of the strip. It is then cross-cut along the lines indicated at 27. The sheet is next folded to assume the shape shown in Fig. 12, and it is then expanded to form the final and finished product shown in Fig. 13. This product is very similar to the product shown in Fig. 3, with the exception that the U-shaped central connectors 28 have been reversed in position, and that additional metal is provided to form the arm-connecting portions indicated at 8a. The portions 8a should preferably be welded to the inner faces of the channel bars shown at 29 and the clips 28 should similarly be welded with relation to each other, thereby materially stiffening and strengthening the product. The product also differs from the structure shown in Fig. 3 in that the side strips, when finally folded, form channel bars 29-29 in place of angle bars as shown in Figs. 3 and 10.

In Figs. 14 to 17, the simplest form of the invention is shown. In Fig. 14 it will be noted that the flat metal strip is only provided with two longitudinal spaced cut portions, as indicated at 30 and 31, and that the cross-cuts indicated at 32 connect the longitudinal cuts. The strip thus cut is folded as shown in Fig. 15. It is then gradually expanded as shown in Fig. 16 to the final position shown in Fig. 17. The central connector between the cross-arms is entirely eliminated. One end of each arm is connected to a channel member as shown at 34 in a manner similar to the connecting portions shown at 8a in Fig. 13. The opposite end of each arm is connected to the web of an angle bar 35 in a manner similar to the connection of the arms shown in Fig. 3. This structure is the simplest in form, and while it is not quite as rigid in construction as that structure shown in Fig. 13, it is on a par with the structure shown in Fig. 3, and perhaps a little more rigid, as the channel bar is formed on one side of the cross-arms while angle bars only are

formed on opposite sides of the cross-arms in Fig. 3.

It will be noted that in all of the structures, cutting and blanking is performed without any waste of metal. Narrow strips of metal may be bent, formed and expanded into structural members of varying width, the width being increased or decreased as desired by merely shortening or lengthening the cross-arms during the first cutting operation. Practically any stiffness or rigidity or load-bearing qualities may thus be obtained, the load-bearing qualities or factor being increased or decreased as desired by the insertion of a central bar channel or like member, as shown in Figs. 4 and 10. All of the structures are open between the cross-arms, this being an exceedingly desirable feature, particularly where the structural members are used as studs in exterior walls or partitions, as it permits pipes, conduits, wiring and the like to be passed through the studs without cutting or in any way weakening them. Also, due to the open construction provided by the cross-arms, it becomes a simple matter to attach clips or tying wires to secure wire lath, expanded metal lath or other forms of lath.

While the structural members here disclosed are shown as formed from strips of sheet metal, I do not wish to limit myself thereto, as the webs of hot rolled channels, I-beams and similar structural members may be cut, formed and expanded in an identical manner, and while these and other features of the present invention have been more or less specifically described and illustrated, I wish it understood that various changes may be resorted to within the scope of the appended claims.

Having thus described and illustrated my invention, what I claim and desire to obtain by Letters Patent is as follows:

1. A structural member of the character described comprising a pair of longitudinally extending spaced side strips, each strip having a web and a flange portion and a plurality of cross-arms formed integral with the web portion of each side strip and connecting the same, said cross arms being disposed at right angles to the side strips and said cross-arms being bent to stand on edge with relation to the flat surfaces of the web members, and a centrally disposed U-shaped connector on each cross-arm.

2. A structural member of the character described comprising a pair of longitudinally extending spaced side strips, each strip having a web and a flange portion and a plurality of cross-arms formed integral with the web portion of each side strip and connecting the same, said cross-arms being bent to stand on edge with relation to the flat surfaces of the web members, and a centrally disposed U-shaped connector on each cross-arm and a longitudinally extending reinforcing bar seated in and secured between the U-shaped connectors.

3. A structural member of the character described comprising a pair of longitudinally extending spaced side strips, each strip having a web and an inner and outer flange, a plurality of cross-arms formed integral with the inner flanges of the side strips and connecting the same, said arms being disposed at right angles to the side strips, and a centrally disposed U-shaped connector on each cross-arm.

TIMOTHY COLLINS.
